CLAIM

The ornamental design for a hand and shoulder bag, as shown and described.

DESCRIPTION

FIG. 1 is a front elevational view of a hand and shoulder bag showing my new design;

FIG. 2 is a rear elevational view thereof with a portion of the shoulder strap broken away and omitted for convenience of illustration;

FIG. 3 is a right end elevational view thereof;

FIG. 4 is a top plan view thereof; and

FIG. 5 is a bottom plan view thereof.
